UNITED STATES PATENT OFFICE.

BERNARD MESS, OF CLEVELAND, OHIO, ASSIGNOR TO THE CLEVELAND SCHOOL FURNITURE COMPANY, OF OHIO.

SEAT-HINGE.

SPECIFICATION forming part of Letters Patent No. 543,883, dated August 6, 1895.

Application filed December 11, 1894. Serial No. 531,513. (No model.)

To all whom it may concern:

Be it known that I, BERNARD MESS, a citizen of the United States, residing at Cleveland, in the county of Cuyahoga and State of Ohio, have invented certain new and useful Improvements in Seat-Hinges; and I do hereby declare the following to be a full, clear, and exact description of the invention, such as will enable others skilled in the art to which it appertains to make and use the same.

The invention relates to seat-hinges for school furniture and other furniture having folding seats.

The object of the invention is to provide a simple, cheap, and substantially noiseless hinge; and the invention consists in the novel construction and combination of parts hereinafter described and claimed.

In the drawings, Figure 1 is an inside elevation (with the cap B removed) of the best form of my improved hinge. Fig. 2 is an inside view of the cap. Fig. 3 is a sectional view of the seat-arm disk on line 3 3. Fig. 4 is a sectional view of the hinge in the plane indicated by line 4 4 of Fig. 1. Figs 5 and 6 are respectively views of the facing sides of the disks on seat-frame and seat-arm, respectively, in a modified and simplified form of the hinge; and Fig. 7 is a sectional view in the plane indicated by line 7 7 in said figures.

I will now describe the form of the hinge shown in Figs. 1 to 4.

A represents a disk which is integral with one of the legs or standards of the seat. It is provided on its lower edge with a rim a , which extends about half around it.

B represents a cap, adapted to be fixed to the disk A by means of the bolt F and the interlocking-lugs b' and depressions a' on said cap and in the rim, respectively. When so secured together they form the fixed member of the hinge-joint.

C represents a disk which is fixed to the seat-arm c . It lies and is adapted to turn in the space between the disk A and cap B, this disk C being the movable member of the hinge-joint. I prefer to construct the disk C with a convex projection on one side, which fits and moves in a corresponding concave depression in the disk A. The extent of the

movement of the movable hinge member is limited by the shoulders a^2 a^2 formed by the ends of the rim a , which engage with the seat-arm c . The lower edge of the disk C may also be cut away, in which case a lug a^3 on the rim a 55 will project into the space thus formed. When the seat is down the lug a^3 will engage with the shoulder c^3 and serve as an additional means for supporting the weight on the seat.

Between the disk C and the cap B lies a flat 60 spring-plate D. A bolt F, which passes centrally through the cap B, the plate D, and disks C and A, secures these parts together.

On the cap B are formed the boss B, which engages with the middle part of the spring- 65 plate, and the ribs b^2 b^2 , between which said spring-plate lies and by which it is prevented from turning on the bolt F.

On the disk C are the projections c' c' , extending toward the cap B and placed at diametrically-opposite points. These projections have beveled ends which are adapted to engage with the spring-plate D near its edges, thereby causing said edges to bend toward the cap B. These projections engage with 70 the spring just before the seat-arm reaches either of its extreme positions, and therefore the spring acts as a buffer, which prevents the sudden coming together of the seat-arm and shoulders a^2 a^2 . This prevents substantially 75 all of the noise which would otherwise be caused by quickly turning the seat up or down and thereby bringing the seat-arm in contact with the said shoulders.

In the form of hinge shown in Figs. 5 to 7 85 the cap is omitted. The boss b and ribs b^2 b^2 are formed on the disk C—the movable member of the hinge-joint. The spring-plate lies against said boss b and between the ribs b^2 b^2 , being thereby held in fixed relation to said 90 movable member, while the projections c' c' are on the fixed member of said hinge-joint—the disk A.

When the disk C is turned upon the hinge-pivot it carries the spring-plate D with it; but 95 before the seat-arm c has reached either of its extreme positions the edges of said spring-plate D come into contact with the beveled projections c' c' , being thereby bent, with the result of checking the movement of said arm 100

and preventing substantially any concussion between the stops on said fixed and movable members.

Other modifications are possible in the embodiment of the invention, and any mechanic will be able to make them when it is understood that the essential characteristics of the invention are the fixed and movable hinge members, a flat spring-plate lying between them, a boss on one of said hinge members bearing against the middle part of said spring-plate, means for holding said plate in fixed relation to the member having said boss, and projections having beveled ends which are formed on the other hinge member and are adapted to engage directly against said spring-plate near its edges.

I regard the form of the device shown in Figs. 1 to 5 as the best form, because the movable disk is held between the disk A and cap B, whereby it is less likely to have any side motion in operation.

Having described my invention, I claim—

1. In a seat hinge, the combination of the fixed and movable members hinged together, a flat spring plate lying between them, a boss on one of said hinge members bearing against the middle part of said spring plate, means for holding the spring plate in fixed relation to said hinge member, and projections with

beveled ends on the other hinge member, which projections are adapted to bear directly against said spring plate when the movable member nears either of its extreme positions, substantially as and for the purpose specified. 35

2. In a seat hinge, in combination, the seat frame, having a disk A, a seat arm, a disk C on said seat arm having the projections $c' c'$ with beveled ends, the cap B having the boss b and the ribs $b^2 b^2$, a flat spring plate lying 40 between said ribs and against said boss, and means for connecting said parts together, substantially as and for the purpose specified.

3. In a seat hinge, in combination, the seat support having a disk A and an incomplete annular rim on said disk, the cap B which interlocks with said rim, the boss b and ribs b^2 on said cap, the seat arm, the disk C on said arm lying between said disk A and cap B, the projections with beveled ends on said disk C, a spring plate E lying between the ribs $b^2 b^2$ and against the boss b , and a bolt F, substantially as and for the purpose specified. 45

In testimony whereof I affix my signature in presence of two witnesses.

BERNARD MESS.
